UNITED STATES PATENT OFFICE.

LUCY MORGAN, OF PECK, KANSAS.

STOVE ATTACHMENT.

1,226,567.

Specification of Letters Patent. Patented May 15, 1917.

Application filed April 5, 1916. Serial No. 89,208.

To all whom it may concern:

Be it known that I, LUCY MORGAN, a citizen of the United States, residing at Peck, in the county of Sedgwick and State of Kansas, have invented certain new and useful Improvements in Stove Attachments, of which the following is a specification.

The present invention has for its object the provision of a simple article of manufacture designed as a protector or shield constituting an attachment for oil stoves or the like and by means of which the stove globe and flame are protected against the result of boiling over of the food containers on the stove. It has been my aim to produce an article of this type such that it may be readily attached and detached from operative position and of a material and form permitting the article to be easily cleaned.

With the above and other objects in view, this invention consists in the construction, combination and arrangement of parts all as hereinafter more fully described, claimed and illustrated in the accompanying drawing, wherein:

Figure 1 is a fragmentary view of a heating device having my protective shield applied thereto;

Fig. 2 is an enlarged sectional view of the shield member; and

Fig. 3 is an enlarged view showing a detail of the globe engaging flange.

Throughout the following detailed description, and on the several figures of the drawing, similar parts are referred to by like reference characters.

Referring to the drawing A designates the globe portion of a conventional type of heating stove and B the support for cooking utensils arranged above the globe. The globe A is provided with an opening to permit of the passage of heat from the stove to act upon a cooking utensil C arranged on the support above said opening.

In constructions of heating devices of this character it is not unusual that the food-stuffs boil over and run down upon the stove globe with the result that the enamel or finish of said globe is soiled and so affected as to make said globe unsightly. Such contact of the boiling material with the globe causes the finish of the body to peel off and the isinglass of the globe door is very materially affected by such accidental happen-

ing. It is with a view to overcoming these disadvantages that I have provided the simple attachment which constitutes the subject matter of my invention.

Said invention consists of a shield 1 which is substantially of dish-shape and is of a greater diameter than the stove globe A with which it is adapted to coöperate. The shield is provided with a central opening which coincides substantially with the size of the opening of the stove globe A and the material of the shield, in the formation of the opening, is first bent upwardly as indicated at 2 to form an upstanding annular flange, and then downwardly to form an inwardly projecting or depending flange 3. In attaching the shield to the stove globe the flange 3 is engaged in the opening of said globe and thereby adequately held from accidental displacement during its use. The bending of the material as indicated at 2 is an important feature inasmuch as the flanging in this manner tends to prevent the overflowing foodstuff from running into the opening of the shield and the stove globe which would result in putting out the flame of the oil stove, or at least affecting said flame in a material manner. The rounding of the surface of the shield and its projection from the body of the globe A prevents the overflowing material from coming in contact with the wall of the said stove globe.

Fig. 3 shows in detail that the flange 3 may be slit and bent outwardly as at 3^a to form one or more engaging projections for contact with the interior of the globe, and then bent inwardly below so as to be easily slipped into position. The members 3^a in attaching the shield to the stove engage beneath the edge of the opening of the stove globe and tend to prevent accidental displacement of the shield from its operative position.

It will be apparent from this description that the article hereinbefore referred to may be cheaply manufactured of suitable size and general configuration to fit different types of stoves and said article forms a neat little attachment which would save much labor on the part of the housewife in maintaining the stove in cleanly condition.

Having thus described my invention, what I claim as new is:

A guard member for attachment directly

to a stove globe provided with a top opening comprising an inverted saucer-shaped deflector having a heat opening centrally thereof, the edge of said opening being formed 5 with an approximately vertical downwardly extending flange with a slitted portion

therein bent outwardly and then inwardly to form a resilient retaining member for engagement with the edges of the globe opening.

In testimony whereof I affix my signature.
LUCY MORGAN.
